Application April 26, 1952, Serial No. 284,491

Claims priority, application France April 27, 1951

8 Claims. (Cl. 66—157)

My invention is concerned with up-to-date high-efficiency knitting machines.

Its object consists in a number of electro-mechanical devices which as a whole constitute something like a complete system for making the actuating members subject to the various safety apparatus as well as controllable at the operator's will.

These improvements, which may be applied separately or in any suitable combination, may be enumerated as follows:

(A) A self-tripping interlocking mechanism providing for the control of the brake as well as for the making and breaking of the various supply and safety circuits.

(B) A remote control system including multiple stations favorably distributed over the periphery of the machine and combined with the aforementioned member for the purpose of conveniently making the operation dependent on the operator's will.

(C) An electro-uncoupler providing for the instantaneous disengagement of the coupling pawl and fed for that purpose with an energizing current controlled by one or several electronic relays responsive to the various safety apparatus.

(D) Means for detecting "holes," "loose stitches," and so on, adapted to actuate the electro-uncoupling mechanism through the medium of an electronic circuit balanced by means of a pair of photoelectric cells suitably arranged in such a manner that the said balance will be upset as soon as a defect in the knitwork appears in the field which either cell has to take care of.

(E) A way of combining the various safety appliances with their control circuits arranged according to the invention with a view to meeting all the eventualities capable of allowing the machine being set into operation or of causing the set to stop instantaneously.

On most knitting frames various safety appliances are provided which are adapted upon the occurrence of such an accident as the breakage of the thread, or of needles, or a defect in the knitwork, to automatically bring the frame to a standstill.

These detectors involve the use of either purely mechanical means or of electro-mechanical combinations capable of stopping the frame as early as possible.

Now, in up-to-date circular knitting frames which are rotated at a considerable speed, the time available to practically bring the machine to a standstill is scarcely less than one tenth of a second.

The consequence is that the various solutions proposed up to the present to automatically stop the machine will no longer satisfy the new requirements of the problem.

The causes of such a failure are multiple. They are ascribable notably to the sluggishness of the relays and electromechanisms and to failures of the contacts and feelers by which they are actuated.

Moreover, some major defects practically escape all known detecting systems. Such are "loose stitches" and "tiny holes" which for want of anything better had to be left to the care of the operator.

On the other hand, as soon as the machine has thus been stopped by such a safety appliance, the man in charge of the frame has to ascertain the causes of the failure, to correct said cause, to re-set the appliance ready and to set the frame again into operation.

Consequently, it became essential not only to resort to additional ultra-sensitive detecting relays, but also as much as possible to facilitate the intricate operations at-

tending the watching at the work and the operation of the frame.

Our invention will be described hereinafter for the purpose of exemplification and not by means of limitation, reference being had to the appended drawings.

Figure 1 is a diagrammatical view which shows the way in which the various subjection and control means may advantageously be arranged and combined.

Figure 2 is a partial view which more particularly shows the explanatory diagram of the interlocking mechanism combined with its remote control means.

Figures 3 and 4 are partial views, in vertical sectional view, of certain details of design belonging to the mechanism represented in plan view in Fig. 2.

Figure 5 is an explanatory diagram which diagrammatically shows an embodiment of the electronic circuits responsive to the rupture of the thread and to the occurrence of a hole respectively and adapted to control the operation of the electro-uncoupler through the medium of a tube relay of the "thyatron" type.

As shown in Figs. 2, 3 and 4 a suitably supported and guided chain 1 is arranged below the main disc of the frame 2. Said chain meshes with sprockets 3, 4 keyed on shafts 5, 6 extending in a hand lever 7.

Each hand lever 7 may assume four particular positions A—B—C—D which respectively correspond to the "Stop," "Slow running," "Brake resetting" and "Quick running" positions.

The chain 1 moreover meshes with a toothed sector 8 keyed on a sleeve 9 and forming a brake-actuating member.

Attached to said sleeve 9 is a brake band 10 the other end of which is secured to a fixed point 11. The band 10 is trained about the brake drum 12 which is rigid with the main driving shaft of the machine 13.

A driving pawl 14 mounted on the pin 15 rigid with the sector 8 can engage below the tooth 17 of ratchet 18 rigid with sleeve 9.

A stop pawl 19 mounted on a fixed pin 20 engages in due time the tooth 21 of a second ratchet 22 likewise rigid with the sleeve 9.

The ratchet pair 18 and 22 which are rigid with the sleeve 9 are mounted loosely as a whole on the fixed pin 23. By the action of the spring 24 attached at either end to sleeve 9 and to the fixed point 25 the ratchets are urged to rotate counterclockwise.

Such a rotation is only possible when pawl 19 is disengaged from tooth 21.

In other terms, the spring 24 is adapted for urging the brake-actuating member 8 towards and up to the position in which it operates the brake formed by the band 10 and the drum 12. The pawl 19 and ratchet 22 act as a locking-catch for retaining the brake actuating member 8 in a cocked and inoperative position.

The disengagement of pawl 19 is controlled in due time by the uncoupling electromagnet 26 acting upon the movable armature constituted by the tail 19a of pawl 19.

The relative position of the interlocking members indicated by the Figs. 1 and 2 is the one obtained when the hand lever 7 is brought to the so-called "Brake resetting" position C. In this position:

(a) The band 10 is released without an action upon the drum 12.

(b) The ratchet 22 engaged on pawl 9 is not responsive to spring 24.

(c) The boss 27 cut in ratchet 18 acts upon the push roll 28 to short-circuit the terminals 29 and 30 of the various control circuits.

(d) The push rolls 32 and 33 of the conventional pattern, urged by their springs, respectively short-circuit the terminals 34—35 and 36—37 belonging to determined circuits the functions of which will be explained herein-after.

(e) The respective circuits leading to terminals 38—39 and 40—41 are cut off.

In the drawing, 42, 43, 44 designate the three main supply wires which lead to the cut-off switch 45.

As soon as said cut-off switch is switched in:

(a) The terminals 46 and 47 feed the primary winding of the transformer 31 which through its secondary

terminals 48—49 provides for the heating of the filament in the tube relay R.

(b) The terminals 47 and 50 of the feed line are live, yet the connection circuit cannot be established as long as the pair of starters 51 and 52 are still open.

The operation of the said starters has been described in the U. S. application Ser. No. 257,248, filed November 20, 1951, by Bernard Lebocey.

The two said starters constitute a safety appliance inasmuch as they will delay by a few seconds the contingent establishment of the current in the driving circuits. This mere precaution practically prevents the starting of the frame into operation before the "thyatron" relay R, once duly heated, is capable of performing its function.

(c) As soon as the ionization process has closed the starters 51 and 52 the cut-off switch is thrown in automatically.

(d) The "Slow-running" motor fed through the three wires 54, 55, 56 remains stopped since the circuit for the energization of its automatic cut-off switch 57 which is fed through the terminals 58—59 of transformer 31 remains open at the terminals 40 and 41 of the push roll 33.

(e) The "quick running" motor fed through the three wires 60—61—62 remains at rest since the circuit adapted to energize its cut-off switch 63, which is likewise fed from the terminals 58—59, is cut off at the terminals 38—39 of the push roll 32.

In order that the frame can be started through the medium of the "Slow-running" motor it is necessary to shift the hand lever 7 from C to B. In this position:

(a) The chain 1 which has moved towards the left and has driven the sector 8 of which the stop 64 has thrust the push roll 33 in such a manner that the two terminals 40 and 41 are now short-circuited while the circuit 36—37 has been cut off.

(b) The current tapped at the terminals 58—59 of the transformer 31 has closed through the points 59—65—66—40—41—67—68—37—30—29—58 on the energizing coil of the automatic cut-off switch 57, and this, on condition that contacts 67—68 are closed.

(c) The closing of contacts 67—68 is controlled advantageously by means of safety appliances known by the names of "clogging detectors" and "broken needle detectors" connected in series with the line.

In normal position the said detectors close the contacts.

Conversely, as soon as any one of said "detectors" has become inoperative, the circuit is broken and obviously the frame cannot be set again into operation until the "detector" concerned has been re-set.

(d) As soon as the hand lever brought to position B is released the spring assigned to push roll 33 by acting upon sector 8 through stop 64 will become effective to move the sector back to the right in such a manner that the said hand lever will assume its normal position at A. The frame is stopped since the circuit is cut off at 40—41.

In order to start the frame into "quick-running" operation it is necessary to shift the hand lever 7 to D-position.

In the said position:

(a) The chain 1 which has moved towards the right has swung the sector 8 in such a manner that its stop 69 by engaging the push roll 32 has thrust the latter to establish contact at 38—39 while temporarily breaking the safety circuit leading to terminals 34—35.

(b) The current tapped at the terminals 58—59 of the transformer 31 will then close through the winding designed to energize the automatic cut-off switch 63 provided the contacts 67—68 are closed, which involves that all the contact-controlling "detectors" are set.

The circuit for the maintenance of the quick operation automatic cut-off switch 63 is thus established through points 58—29—30—37—36—66—65—59.

(c) In the course of such a swinging motion the sector 8 has also moved the pawl 14 the tail 14a of which has come into engagement with the fixed stop 70 in such a manner that said pawl 14 has disengaged tooth 17, whereby ratchet 18 has been released quite temporarily.

The consequence of such an arrangement is that whenever the electromagnet 26 is operated and thereby becomes effective to attract pawl 19 and release the interlocking mechanism the spring 24 will rotate the sleeve

9 providing the locking of the brake by the tension of the band 10.

On the other hand the ratchet 18 rigid with ratchet 22 will rotate therewith. The boss 27 will cease to act upon the push roll 28 which instantaneously will cut off the circuit leading to the terminals 29 and 30.

As a consequence of the cutting off of the holding circuit for the automatic cut-off switch 63 the "quick running" motor will be stopped instantaneously.

Consequently, it will only be necessary to energize the electro-uncoupler 26 to cut off the supply to the "quick running" motor and simultaneously causing the automatic release of the brake.

The energization of the electromagnet 26 may be controlled by the whole or part of the various safety appliances.

With this end in view, the aforementioned arrangement may advantageously be combined with the so-called "electronic thread-rupture detector" providing the subject-matter of the aforementioned application.

The same arrangement may also be combined with electronic means adapted to detect "holes" or "loose stitches."

According to the invention, an embodiment of such a combination will be described hereinafter by way of example, reference being had to Figs. 1 and 5 of the appended drawings:

The feed of the electro-uncoupler 26 is ensured from the secondary terminals 0—71 of the transformer 72, the circuit being operated through a tube of the "thyatron" type R the heating of the filament of which is ensured previously through the transformer 31 as indicated pre-cedingly.

According to an improvement of the invention according to the arrangement provided in the aforementioned application the feed of the grid potential may be effected crosswise to the potential 73 and of the rectifier 74 from the pair of terminals 75 and 76 of the filament heating circuit.

It will be recalled that the accidental fall of the detector tumbling arm 77 which normally is kept in its raised position by the thread 78 has for its effect to earth the antenna 79, a circumstance which is sufficient to destroy the normal grid-biasing potential. The cathode-anode circuit will then be established in the relay R and the electro-magnet 26 releases the brake and stops the machine.

This arrangement may moreover be combined with the "electronic hole and loose-stitch detector."

The said "electronic detector" is intended to stop the frame as soon as a defective place in the web (holes, loose stitches, and so on) appears in the field assigned to one or several photoelectric cells.

According to a new example of achievement and application which will be described hereinafter, reference being had to the Figs. 1 and 5, a pair of suitably directed and supported photoelectric cells 80 and 81 permanently scan two different areas of the periphery of the knitwork web N, which web assumes the shape of a practically cylindrical tube which is comparatively transparent as it leaves the needles. One or several projection lamps 82 favorably arranged within said tubular web emit light bundles capable of influencing the two sensitive cells through the knitwork.

The two cells 80 and 81 are fed through the secondary terminals 83 and 84 arranged at either side of the terminal O which is earthed.

The two cells 80 and 81 are in series in the circuit, their connection being established in the cathode-anode direction from terminal 83.

A point P, taken in the circuit, between the anode of cell 80 and the cathode of cell 81 is connected with the grid of the thyatron tube R.

In normal working, it may be admitted that the relative transparency of web N, considered at the same time in the scanning field of the two cells remains substantially the same. The two cells collect each a light flux of equal intensity, their internal resistances are, at that very moment, practically similar and the potential of P is evidently well defined.

In these conditions, considering only the half period during which the thyatron anode is positive, which condition after all is necessary to prime the relay, it will be seen that the potential of the terminal 84 is necessarily

positive, whereas that of terminal 83 at that time is negative relative to point O.

Consequently, it is always possible to choose the conditions of balancing of points 83 and 84 in such a manner that the potential of P will always assume a negative value which in its absolute value is higher than or equal to the one necessary to cause the "thyatron" grid to prevent the priming of the relay, and this, in normal working conditions.

It being assumed that a "hole" or a "loose stitch" appears accidentally in the field of cell 80, whereby the light flux striking the cathode is increased, it is evident that the internal resistance of said cell will decrease, thus creating a disequilibrium which will be translated into a variation in the potential of P, which will become closer to the negative potential of the terminal 83, thus aggravating the grid locking conditions.

Quite the contrary, as soon as the aforesaid hole appears in the field of cell 81, the same process will go on except that since the potential of P becomes closer to that of the positive terminal 84 it will be enabled to assume a positive value which is sufficient to set the relay out of balance, and thereby to initiate the energization of the electro-uncoupler 26 by which the frame will be stopped instantaneously.

However, the conditions of utilization of such a device require certain complementary arrangements.

Effectively, as soon as the uncoupler has functioned, the operator must be enabled to take the defective place out of the field of the cell concerned and to start the frame into operation again.

With this end in view, the cell feed circuit is provided with a cut-off at the terminals 34-35 which in normal working conditions are short-circuited by the push 32.

Consequently, it is only necessary for the operator to swing the hand lever 7 back from A to C to keep said lever a few seconds in the last-mentioned position, as a result of which the frame is re-started into "Quick-running" operation while the said circuit will be cut off for sufficient time to allow the defective place to move away before the safety circuit considered is re-established.

On the other hand, it may prove desirable to provide for a complementary safety device intended to become effective in the event the thyatron relay should happen to fail.

With this end in view, an auxiliary relay 85 is provided the operation of which is as follows:

As soon as the thread happens to fall with the feeler arm the electronic frame stop comes into action. If the latter in its turn happens to fail, e. g. consequent to the thyatron tube getting out of order, thread will begin to clog the needle hooks, as a consequence of which the "clogging detector" are moved upwards and thereby provide for the opening of the aforesaid contacts 67-68.

At that moment the relay 85 which is no longer energized will release its movable armature 86 by which the terminals 87 and 88 are short-circuited.

The circuit is then closed to earth between the terminals 0 and 71 and the coil 26 mounted in series in the same circuit will bring the frame to a standstill.

What I claim is:

1. In a circular knitting machine having a plurality of motor control-and-safety circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control-and-safety-circuits of the machine, at least one common hand-operated member having a driving connection with said brake-actuating member, and thereby adapted for shifting back said brake-actuating member from its operative to its cocked and inoperative position against the stress of the spring, said hand operated member being lockable in several different positions in which the circuit control means operatively associated with the brake-actuating member set in operation different motor control-and-safety-circuits, an electromagnet having its armature connected to the aforesaid locking catch, and means responsive to the defects in operation of the knitting machine, adapted for electric action upon the energizing circuit of said electromagnet and for consequent unlocking of said locking catch, which results in the release of the brake-actuating member up to its operative position and in the timely operation of the different motor- and safety-circuits of the machine.

2. In a circular knitting machine having a plurality of motor- and safety-circuits among which are a slow running motor-circuit and a quick-running motor-circuit, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control-means operatively associated with said brake-actuating member for timely operating the motor- and safety-circuits of the machine, at least one common hand-operated member having a driving connection with said brake-actuating member and thereby adapted for shifting back said brake-actuating member from its operative to its cocked and inoperative position against the stress of the spring, said hand-operated member being lockable in several different positions in which the circuit-control means operatively associated with the brake-actuating member set in operation different motor- and safety-circuits and among which are a slow running motor-circuit position and a quick running motor-circuit position, an electromagnet having its armature connected to the aforesaid locking catch, and means responsive to the defects in operation of the knitting machine, adapted for electric action upon the energizing circuit of said electromagnet and for consequent unlocking of said locking catch, which results in the release of the brake-actuating member up to its operative position and in the timely operation of the different motor- and safety-circuits of the machine.

3. In a circular knitting machine having a plurality of motor control- and safety-circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control- and safety-circuits of the machine, at least one common hand-operated member having a driving connection with said brake-actuating member, and thereby adapted for shifting back said brake-actuating member from its operative to its cocked and inoperative position against the stress of the spring, said hand-operated member being lockable in several different positions in which the circuit control means operatively associated with the brake-actuating member set in operation different motor control- and safety-circuits, an electromagnet having its armature connected to the aforesaid locking catch, and means responsive to the defects in operation of the knitting machine, adapted for electric action upon the energizing circuit of said electromagnet and for consequent unlocking of said locking catch, which results in the release of the brake-actuating member up to its operative position and in the timely operation of the different motor- and safety-circuits of the machine.

4. In a circular knitting machine having a plurality of motor control- and safety-circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control- and safety-circuits of the machine, at least one common hand-operated member having a driving connection with said brake-actuating member, and thereby adapted for shifting back said brake-actuating member from its operative to its cocked and inoperative position against the stress of the spring, said hand-operated member being lockable in several different positions in which the circuit control means operatively associated with the brake-actuating member set in operation different motor control-and-safety-circuits, an electromagnet having its armature connected to the aforesaid locking catch, and means responsive to the defects in operation of the knitting machine, adapted for electric action upon at least one grid of said thyatron tube and for consequent unlocking of the locking catch connected to the armature of the electromagnet, which results in the release of the brake-actuating member up to its operative position and in the timely operation of the different motor- and safety-circuits of the machine.

5. In a circular knitting machine having a plurality of motor control- and safety-circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control- and safety-circuits of the machine, at least one common hand-operated member having a driving connection with said brake-actuating member, and thereby adapted for shifting back said brake-actuating member from its operative to its cocked and inoperative position against the stress of the spring, said hand-operated member being lockable in several different positions in which the circuit control means operatively associated with the brake-actuating member set in operation different motor control-and-safety-circuits, an electromagnet having its armature connected to the aforesaid locking catch, and means responsive to the defects in operation of the knitting machine, adapted for electric action upon the energizing circuit of said electromagnet and for consequent unlocking of said locking catch, which results in the release of the brake-actuating member up to its operative position and in the timely operation of the different motor- and safety-circuits of the machine.

cuit control means operatively associated with the brake-actuating member set in operation different motor control- and safety-circuits, an electromagnet having its armature connected to the aforesaid locking catch, a thyratron tube having its cathode-anode circuit connected to the energizing circuit of said electromagnet, and a thread rupture responsive detector adapted for electric action upon a grid of said thyratron tube and for consequent unlocking of the locking catch connected to the armature of the electromagnet, which results in the release of the brake-actuating member up to its operative position and in the timely operation of the different motor- and safety-circuits of the machine.

5. In a circular knitting machine having a plurality of motor control- and safety-circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control- and safety-circuits of the machine, at least one common hand-operated member having a driving connection with said brake-actuating member, and thereby adapted for shifting back said brake-actuating member from its operative to its cocked and inoperative position against the stress of the spring, said hand-operated member being lockable in several different positions in which the circuit control means operatively associated with the brake-actuating member set in operation different motor control- and safety-circuits, an electromagnet having its armature connected to the aforesaid locking catch, a thyratron tube having its cathode-anode circuit connected to the energizing circuit of said electromagnet, a pair of photoelectric cells having their scanning field directed upon two different areas of the periphery of the knit work of the circular knitting machine and electrically connected for differential action upon a grid of the thyratron tube, thereby adapted to produce an electric action upon the energizing circuit of the electromagnet and consequently to stop the machine whenever a defect appears in the scanning field of one of the cells.

6. In a circular knitting machine having a plurality of motor control- and safety-circuits, a control device comprising a brake adapted to stop the working of the machine, a brake-actuating member for said brake, a spring adapted for urging said brake-actuating member toward and up to its operative position, a locking catch for retaining said brake-actuating member in a cocked and inoperative position against the stress of the spring, circuit control means operatively associated with said brake-actuating member for timely operating the motor control- and safety-circuits of the machine, at least one common hand-operated member having a driving connection with said brake-actuating member, and thereby adapted

for shifting back said brake-actuating member from its operative to its cocked and inoperative position against the stress of the spring, said hand-operated member being lockable in several different positions in which the circuit control means operatively associated with the brake-actuating member set in operation different motor control- and safety-circuits, an electromagnet having its armature connected to the aforesaid locking catch, a thyratron tube having its cathode-anode circuit connected to the energizing circuit of said electromagnet, a thread rupture responsive detector adapted for electric action upon a grid of said thyratron tube and for consequent unlocking of the locking catch connected to the armature of the electromagnet, which results in the stopping of the machine upon occurrence of a thread rupture, a pair of photoelectric cells having their scanning field directed upon two different areas of the periphery of the knit work of the circular knitting machine and electrically connected for differential action upon a grid of the thyratron tube, thereby adapted to produce an electric action upon the energizing circuit of the electromagnet and consequently to stop the machine whenever a defect appears in the scanning field of one of the cells.

7. In a circular knitting machine having a plurality of motor control- and safety-circuits, a control device as claimed in claim 1, and irreversible clogging-responsive circuit breakers inserted in the motor control-circuits and adapted to cut off the power circuits of the motors when set in the breaking position, whereby a hand resetting of said circuit breakers to their closed position must be effected prior to any restarting of the motors.

8. In a circular knitting machine having a plurality of motor control- and safety-circuits, a control device as claimed in claim 3, irreversible clogging-responsive circuit breakers inserted in the motor control circuits and adapted to cut off the power circuits of the motors when set in the breaking position, whereby a hand resetting of said circuit breakers to their closed position must be effected prior to any restarting of the motors, and an auxiliary clogging-responsive relay adapted for direct electric action independent of the thyratron tube upon the energizing circuit of the aforesaid electromagnet, providing thus a complementary safety device intended to become effective in the event of failure of the thyratron tube.
